Primary Examiner—Cathron Brooks*Assistant Examiner*—Rosemary K Tarcza(74) *Attorney, Agent, or Firm*—Merchant & Gould P.C.(57) **CLAIM**

The ornamental design for the fiber trough base, as shown and described.

DESCRIPTION

FIG. 1 is a top perspective view of the fiber trough base.

FIG. 2 is a first bottom perspective view thereof.

FIG. 3 is a second bottom perspective view thereof.

FIG. 4 is a first end view thereof.

FIG. 5 is a first side view thereof.

FIG. 6 is a second side view thereof.

FIG. 7 is a second end view thereof; and,

FIG. 8 is a bottom view thereof.

The broken line showing aspects of the fiber trough horizontal T component is for the purpose of illustrating environmental structure and forms no part of the claimed design.
